UNITED STATES PATENT OFFICE

GUY ROBINSON, OF DINUBA, AND HAROLD CLAUSEN, OF ALAMEDA, CALIFORNIA

HANGER

Application filed February 27, 1928. Serial No. 257,250.

The invention relates to suspensible hangers arranged for use in effecting a suspended support of various articles from a fixed supporting means and in adjusted relation thereto.

An object of the invention is to provide hangers of the character described which are particularly adapted for use in supporting relatively flat objects such as floral pieces and the like.

Another object of the invention is to provide like and unitary hanger members which are arranged for use either singly or in combination, as may be required.

15 A further object of the invention is to provide hangers of the character described having improved means for attaching them to a fixed support or to each other.

A still further object of the invention is 20 to provide unitary hanger members of the character described which are adapted to be formed of a single piece of material in a particularly simple manner whereby their cost of production is a minimum.

25 The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as 30 set forth in the claim.

35 Referring to said drawing,

Figure 1 is a perspective view of a pair of the hanger units, one of the units being supported from a fixed object and the other unit being supported from the first.

40 Figure 2 is an enlarged perspective view of one of the hanger units.

Figure 3 is a face view of a blank from which a hanger unit is arranged to be shaped.

45 Essentially, the hanger units of the inven-

tion comprise unitary members 5 each providing an attaching hook 6 at its upper end, at least one supporting hook 7 intermediate its structure, and means whereby the attaching hook 6 of one member may be used to support such member from another one of the members. The units 5, it is noted, are particularly designed for use in removable installations, and the hooks 6 are accordingly so formed as to removably engage over 50 a suitable fixed and generally horizontally disposed support such as a wire, a picture mold, or a railing—as disclosed in Figure 1, the upper unit is supportably engaged with a wire 8. It will usually be preferable that 55 the hook 6 be formed to extend in part forwardly of the general plane of the unit whereby the axis of support provided thereby may not lie so far rearwardly of said plane as to cause an undue tilting of the unit when 60 freely suspended.

The hanger unit, it will now be noted, is arranged to be formed of a blank 9 comprising a length of ribbon of metal or other relatively stiff material. The upper end of the blank is 65 formed to provide a pair of longitudinally extending and spaced tines 11, such tines being preferably provided by notching the end of the blank from its free extremity whereby edge portions thereof at such end form the 70 outer edges of the tines and the latter are spaced to a maximum amount. The hook 6, it will now be noted, is cylindrically curved about an axis parallel to the general plane of the blank and perpendicular to its longitudinal axis, it being noted that this relation 75 of the hook 6 to the unit provides for a line support thereof on the wire 8 whereby a swinging of a hanger unit in the plane of the wire and said unit is resisted, and the unit 80 therefore tends to maintain a fixed position in said plane.

The article supporting hook 7 is also arranged to comprise an integral portion of the structure, and the blank is accordingly 85

slotted diagonally upwardly from the point at one edge thereof to provide a V-shaped tongue 12, which, when bent outwardly and upwardly to the general shape shown, provides the hook 7. Preferably, and as shown, the hook 7 is provided somewhat above the midpoint of the unit whereby the lower portion of the unit may provide a backing for an article suspended from the hook and thereby steady such article against movement both transversely and laterally of the plane determined by the unit and its axis of support. The tines 11, it will now be noted, are primarily provided for effecting a support of one hanger unit from another, and the lower end of each unit designed for supporting another is accordingly formed with one or more sets of notches 13 whereby the unit is so reduced in width thereat that the different tines 20 of the unit to be supported may be disposed in the notches of a set of the first unit for supporting the second unit thereon. As shown, the notches 13 are of right triangular outline with the lower end supporting edges 25 14 thereof perpendicular to the longitudinal axis of the unit. In the present instance, two sets of the notches 13 are shown whereby the position of a suspended unit may be adjusted with respect to a unit from which it is hung. Preferably, all of the units 5 are formed alike, it being obvious, however, that in units not designed for supporting others, the tines 11 and notches 13 might be omitted.

The units now described are particularly designed for use in effecting the support of decorative members in a vertical plane, either against a wall, or spaced from all walls. Any required number of the units may be used in a string thereof, and any number of strings 40 of units may be used for supporting decorations in the form of a screen if such is desired. By mounting the upper units on a horizontal wire, or a similar support, lateral adjustment thereof is provided for, which fact, coupled with the vertical adjustment provided for between connected units, permits any desired distribution of the support hooks 7 in the area to be decorated.

From the foregoing description of a unit 5 embodying the present invention, it will be obvious that the different parts of a unit are integrally associated, and that the completed unit is arranged to be formed of the blank 9 in a particularly simple manner. In fact, the form of the blank is such that it may be readily cut and shaped to form a hanger unit entirely by machine means, and thus the units may be quickly and economically produced, it being also noted that a minimum waste of material results in forming the blank.

If desired, an extreme lower end portion 16 of the blank below the lower notches 13 may be bent angularly rearwardly as shown to provide a spacing means for the lower end 65 of the unit. In this manner, when one or

more units are hung against a wall (not shown), they will be held spaced therefrom and more nearly vertical.

We claim:

A hanger unit formed of a strip of flat 70 material having its upper end curved out of the plane of the strip to provide a hook thereon, said hook including parallel spaced tines at the extremity thereof, and said strip being notched at opposed edge points thereof 75 to provide a constriction of no greater width than is the space between said tines whereby the tines of a second hanger unit having a hook formed like the hook of said first unit may engage in said notches for supporting 80 the second unit on the first.

In testimony whereof, we have hereunto set our hands.

GUY ROBINSON.

HAROLD CLAUSEN.
